Primary Examiner — Jennifer Rivard

(57) **CLAIM**

The ornamental design for a razor cover, as shown and described.

DESCRIPTION

FIG. 1 is a front perspective view of the razor cover.
FIG. 2 is a front view thereof.
FIG. 3 is a back view thereof, opposite the view of FIG. 2.
FIG. 4 is a right side view thereof.
FIG. 5 is a left side view of thereof, opposite the view of FIG. 4.
FIG. 6 is a top view of thereof.
FIG. 7 is a bottom view thereof, opposite the view of FIG. 6; and,
FIG. 8 is a bottom perspective view thereof.
The broken lines illustrate portions of the razor cover and form no part of the claimed design.
The word intuition including the design feature two intersecting circles is a registered trademark of Edgewell Personal Care Brands, LLC, the applicant and assignee of the present disclosure, and is shown in broken lines on FIGS. 1-2, and thus forms no part of the claimed design.
